FIG. 1 is a perspective view of the billed cap, showing several golf tees inserted under the elasticized band attached to the bill;

FIG. 2 is a front elevation view thereof;

FIG. 3 is a rear elevation view thereof;

FIG. 4 is a side elevation view thereof;

FIG. 5 is a side elevation view, thereof, viewed from the side opposite FIG. 4;

FIG. 6 is a top plan view thereof; and,

FIG. 7 is a bottom plan view thereof.

The broken line showing of the golf tees in FIGS. 1,2,4,5, and 6 is for illustrative purposes only and forms no part of the claimed design.
